UNITED STATES PATENT OFFICE.

RICHARD B. M. COLVIN, OF FALMOUTH, KENTUCKY.

DESIGN FOR A HARNESS ATTACHMENT.

SPECIFICATION forming part of Design No. 31,041, dated June 20, 1899.

Application filed May 22, 1899. Serial No. 717,860. Term of patent 7 years.

To all whom it may concern:

Be it known that I, RICHARD B. M. COLVIN, a citizen of the United States, residing at Falmouth, in the county of Pendleton and State 5 of Kentucky, have invented and produced a new and useful Design for a Harness Attachment, of which the following is a specification, reference being had to the accompanying drawing hereto attached, and in which I 10 have shown a perspective view of the attachment constructed in accordance with my design, the essential feature of my invention consisting in the peculiar shape and configuration thereof, which will be fully described 15 hereinafter and pointed out in the claim.

Referring to the drawing, A represents a flat metallic band having circular perforations A' produced therein. The band is curved or bent upon itself, as shown at B,

and adjacent to the curved end a tongue C is 20 struck up from the body of the band, said tongue being curved at C', as shown. The curved portion of the band is also concaved, as shown at B', providing a convexity upon 25 the inner face of the strap in order to avoid wearing the reins, it being understood that the strap is attached to a portion of the harness and serves as a rest for the reins.

Having thus fully described my invention, what I claim as new, and desire to secure by 30 Letters Patent, is—

The design for a harness attachment, substantially as herein shown and described.

RICHARD B. M. COLVIN.
